UNITED STATES PATENT OFFICE.

NELLIE H. FOSE, OF APPLETON, WISCONSIN.

SANITARY SKIRT-SHIELD.

1,182,262.

Specification of Letters Patent.

Patented May 9, 1916.

Application filed June 18, 1913. Serial No. 774,459.

To all whom it may concern:

Be it known that I, NELLIE H. Fose, a citizen of the United States, residing at Appleton, in the county of Outagamie and State of Wisconsin, have invented a new and useful Sanitary Skirt-Shield; and I do hereby declare the following to be a full, clear, and exact description of the invention, such as will enable others skilled in the art to which it appertains to make and use the same.

This invention relates to improved sanitary skirt shield.

An object of the invention is the provision of a skirt having a skirt shield permanently carried thereby, and adapted to be worn during the catamenial or menstrual period, for protecting the outer clothing of the wearer.

A feature of the invention is the provision of a tongue member forming an integral part of the shield, to be bent downwardly and curved forwardly and arranged in the crotch of the wearer, under the usual garment shields, with its forward end attached to a portion of the clothing of the wearer. A shield of this nature including the tongue acts more thoroughly in protecting one's clothing, whether in a standing or sitting position, and owing to the shield and tongue being constructed of waterproof material, there is no chance of the moisture or fluid being absorbed sufficiently as to be seen upon the outside of the wearing apparel.

In practical fields the details of construction may necessitate alterations, to which the patentee is entitled, provided the alterations fall within the scope of what is claimed.

The invention comprises further features and combination of parts, as hereinafter set forth, shown in the drawings and claimed.

In the drawings: Figure 1 is a view showing the skirt as constructed with the improved sanitary skirt shield. Fig. 2 is a sectional view. Fig. 3 is a detail view showing the skirt shield and the tongue, prior to the same being made a permanent part of the skirt. Fig. 4 is a transverse sectional view through the skirt.

Referring to the drawings, 1 designates the skirt proper, which is constructed in two parts, the forward part 2 which extends par-

tially to the rear and the rear part 3. These parts are sewed together as at 4, thereby forming a stitched plait, to which the vertical edges 5 of the shield proper 6 are likewise stitched as at 7. The horizontal edge portions of the shield are also stitched at 8 to the skirt. About one third down from the top edge or band of the skirt, adjacent each side, the forward and rear portions are left unstitched, forming plackets 10, the edges of which are hemmed in the usual manner.

The band of the upper portion of the rear part of the skirt is provided with a series of eyes, while each end of the band of the forward portion is provided with a hook. By the provision of hooks and eyes, the skirt may be made or adjusted to fit waists of different dimensions, the hooks and eyes being designated by the numerals 11 and 12.

The upper edge portion of the shield proper is provided with an integral tongue 13, which is adapted to be bent downwardly, forwardly, and arranged in the crotch of the wearer below the usual shield garments, with the end of the tongue having a fastener 14 for securing the same to a portion of a wearing apparel. This tongue may be used, however, in lieu of the usual shield garment ordinarily worn during the above named period.

From the foregoing it is apparent that there has been devised a simple and efficient sanitary skirt shield adapted for permanent connection with a skirt especially constructed, and one which has been found desirable and practical.

The invention having been set forth, what is claimed as new and useful is:—

In combination, an underskirt comprising a piece designed to substantially surround the body of the wearer and having its adjacent end edges nearly meeting; a set-in piece being stitched to the nearly meeting edges of the first piece; a water proof sanitary shield of a length shorter than the set-in piece, and having its upper and lower ends stitched transversely to said set-in piece, and having its side edges also stitched to the nearly meeting edges of the first piece; said shield having at its upper edge, which

is offset below the upper ends of the set-in piece, an integral tongue, designed to be bent downwardly and curved forwardly and arranged in the crotch of the wearer, thereby 5 acting to perform the dual purpose of a bandage support at one time and as a shield or protector at all other intervening periods.

In testimony whereof I have signed my name to this specification in the presence of two subscribing witnesses.

NELLIE H. FOSE.
